POWDER SPRAYER

Frank R. Chester, Santa Monica, Calif.

Application November 19, 1945, Serial No. 629,380

11 Claims. (CL 222—193)

1

My invention relates to a powder sprayer or duster.

One of the principal objects of this invention is to provide a simple and economical article of manufacture whereby powder of various kinds, such as talcum, insecticide, and the like, may be sprayed, and thereby more or less finely and uniformly spread, dispersed, or dusted.

Another important object of this invention is to provide means of finely and uniformly spreading, dispersing or dusting powder in connection with or on a flexible and resilient bulbous container, and a container from which such means may be readily removed so that the container may be readily refilled with powder.

An important object also is to provide a means of this class in connection with or on such a bulbous container whereby air may be quickly or readily drawn into the container, but from which the air may be exhausted at a much slower rate while powder is suspended in the exhausted air.

A further important object of this invention is to provide simple and economical means of causing the powder to be blown uniformly from the container and suspended in and spread with the exhausted air.

Still another important object of this invention is to provide an article of this class which may be used interchangeably as a powder spreader or a syringe.

With these and other objects in view, as will appear hereinafter, I have devised a powder sprayer having certain novel features of construction, combination, and arrangement of parts and portions, as will be hereinafter described in detail and particularly set forth in the appended claims, reference being had to the accompanying drawings and to the characters of reference thereon, which form a part of this application, in which:

Fig. 1 is a longitudinal sectional view of my powder sprayer in one form of construction, showing by dotted lines the reverse position of the nozzle;

Fig. 2 is a fragmentary longitudinal section, showing a modified form of the construction of the nozzle, which may also be reversed;

Fig. 3 is a fragmentary sectional view of the normally inner end of the nozzle when the device is used as a powder sprayer, or the outer end of the nozzle when the device is used as a syringe;

Fig. 4 is a fragmentary longitudinal section of my device, showing another slightly modified form of a spray nozzle therefor; and,

2

Fig. 5 is a transverse sectional view thereof, taken through 5—5 of Fig. 4.

The container for holding the product to be spread, dispersed, or dusted, designated 1, is a contractable container, and is preferably of a compressible bulbous form, such as the rubber bulbs commonly used in syringes.

The neck 1^a of the bulbous container has a relatively large opening 1^b, which is hereinafter referred to as the filling opening. The walls of this opening preferably have internal threads 1^c for receiving an enlarged externally threaded portion 2^a of a nozzle member 2. This nozzle member has an axially inwardly extending tubular portion 2^b, which has a constricted opening 2^c at its inner end.

At the outer end of the nozzle member, and in axial alignment with the tubular portion 2^b, is a recess 2^d in which is secured, preferably frictionally, a nozzle tip 3, which is of inverted cup shape. The cylindrical side wall portion extends into and engages the side wall of the recess 2^d; and the head end 3^a, which is rounded, is positioned beyond the outer end of the nozzle member 2. This rounded end has a plurality of diverging orifices 3^b for spraying the contents of the container as they are forced outwardly by the compression of the bulb or the bulbous container 1.

When the nozzle member 2 is removed, a relatively large opening is provided in the container 1 for filling the same with powder. When the nozzle member is screwed into position, compression of the bulbous container will cause the powder to be discharged through the tubular portion 2^b and dispersed, spread, or dusted from the nozzle tip 3. The constricted inner end 2^c causes a limited amount of powder to be blown from the container, and is immediately allowed to spread or be suspended in the air also blown therefrom. It is further spread or expanded when discharged through the orifices 3^b.

When desiring to use the article as a syringe, the nozzle member is merely reversed, with the tubular portion 2^b directed outwardly, as indicated by dotted lines in Fig. 1. In such condition, water or other liquid within the bulbous container may be forced in the direction desired.

In the modified form shown in Fig. 2, the nozzle member, designated 4, is shown as being merely pressed within the opening 1^b of the bulbous container and is held therein by an annular ridge 1^d. In this modification, the outer end of the nozzle member is axially extended, as indicated by 4^a, providing an extended powder spreading,

dispersing, or dusting tip 4^b. This nozzle member may be also reversed, as described in connection with the illustration in Fig. 1.

In Fig. 3, one end of the nozzle member, designated 5, which is the inner end when the article is used as a powder sprayer, has an axial bore 5^a and transverse ports 5^b at the inner end, for conducting powder to the axial bore 5^a.

In the modification shown in Figs. 4 and 5, the only nozzle member is an element 6, which is also of inverted cup shape, rounded at the outer end, as indicated by 6^a, provided with diverging orifices 6^b. The cylindrical walls 6^c of the nozzle member are frictionally secured to the walls of a recess 7^a at the outer end of a discharge passage 7^b of the compressible bulbous member 1. Between the inner end of the nozzle member and an annular shoulder 7^c at the inner end of the recess 7^a, is a washer 8 having a central orifice or port 8^a, which is relatively large. Near the inner end of the discharge passage 7^b is a grid formed by axially extending the ribs 9. These ribs provide, at their upper or outer ends, shoulders 9^a. In the space between the inner side of the washer 8 and the shoulders 9^a is a floating valve disc 10, which may be made of rubber. This disc is considerably smaller in diameter than the space inwardly of the washer 8 but larger than the inner portions of the ribs 9. The disc has a central orifice or port 10^a which is considerably smaller than the orifice or port 8^a. With such an arrangement, inward drawing of air will cause the valve disc to rest upon the shoulders 9^a and allow a large quantity of air to enter the compressible bulbous container, and compressing of the container will cause air to force the valve disc against the inner side of the washer 8 and allow only a small amount of air and powder, or other contents of the container, to be discharged therethrough and from the orifices 6^b at the outer end of the nozzle tip.

Though I have shown and described a particular construction, combination, and arrangement of parts and portions, and certain modifications thereof, I do not wish to be limited to the same, but desire to include in the scope of my invention the construction, combination, and arrangement of parts and portions substantially as set forth in the appended claims.

I claim:

1. In an article of the class described, a compressible container having a discharge passage, an apertured valve seat in said passage, and valve means provided with a smaller aperture cooperating with said seat to provide a large opening for air intake and a small opening for discharge of a portion of the contents of the container.

2. In an article of the class described, a compressible container having a discharge passage with spraying means at its outer end, an apertured valve seat in said passage, and valve means provided with a smaller aperture cooperating with said seat to provide a large opening for air intake and a small opening for discharge of a portion of the contents of the container.

3. In an article of the class described, a container having a discharge passage having a recess intermediate its ends communicating through a port means with the outer end of the passage, and having a grid at the inner side of the recess, and a floating valve disc in the recess provided with a port means smaller than the former port means, said valve disc being capable of resting on the grid with intake of air and capable of being

positioned over the first port means when discharging a portion of the contents of the container.

4. In an article of the class described, a container having a discharge passage, with spraying means at its outer end, having a recess intermediate its ends communicating through a port means with the outer end of the passage and having a grid at the inner side of the recess, and a floating valve disc in the recess provided with a port means smaller than the former port means, said valve disc being capable of resting on the grid with intake of air and capable of being positioned over the first port means when discharging a portion of the contents of the container.

5. A collapsible container adapted to receive fluent material to be dispensed therefrom, said container having a reduced neck portion provided with an aperture therein, a nozzle member disposed in said aperture, interengaging means on said nozzle and said container for retaining said nozzle in position in said aperture, said nozzle being provided with a longitudinal passage terminating at its inner extremity in a reduced aperture communicating with the interior of the container, said nozzle being further provided with a spraying head at its outer extremity, and means for dispersing fluent material within said spraying head prior to discharge therefrom.

6. A collapsible container adapted to receive fluent material to be dispensed therefrom, said container having a reduced neck portion provided with an aperture therein, a nozzle member disposed in said aperture, interengaging means on said nozzle and said container for retaining said nozzle in position in said aperture, said nozzle being provided with a longitudinal passage terminating at its inner extremity in a reduced aperture communicating with the interior of the container, said nozzle being provided with a spraying head at its outer extremity, the average diameter of said passage outwardly of said neck portion being substantially greater than the diameter inwardly thereof, whereby fluent material dispensed through said passage will disperse therein prior to discharge.

7. A collapsible container adapted to receive fluent material to be dispensed therefrom, said container having a reduced neck portion provided with an aperture therein, a nozzle member disposed in said aperture, interengaging means on said nozzle and said container for retaining said nozzle in position in said aperture, said nozzle being provided with a longitudinal passage terminating at its inner extremity in a reduced aperture communicating with the interior of the container, said nozzle being further provided at its outer extremity with an enlarged bore coaxial with said passage and communicating therewith, a hollow spraying head positioned within said bore, the internal diameter of said spraying head being substantially greater than the diameter of said passage whereby fluent material dispensed therethrough will disperse within said head prior to discharge.

8. A collapsible container adapted to receive fluent material to be dispensed therefrom, said container having a reduced neck portion provided with an aperture therein, a nozzle member disposed in said aperture, interengaging means on said nozzle and said container for retaining said nozzle in position in said aperture, said nozzle projecting on both sides of said neck portion and being provided with a longitudinal passage terminating at its inner extremity in a

reduced aperture communicating with the interior of the container, said nozzle being further provided with a spraying head at its outer extremity, the diameter of said passage being progressively increased outwardly of said neck portion, whereby fluent material dispensed through said passage will disperse therein prior to discharge.

9. A collapsible container as described in claim 7 where said reduced aperture is disposed transversely of said passage at the inner extremity thereof.

10. A collapsible container as described in claim 8 where said reduced aperture is disposed transversely of said passage at the inner extremity thereof.

11. A collapsible container adapted to receive fluent material to be dispensed therefrom, said container having a portion provided with an aperture therein, a nozzle member disposed in

said aperture, means for retaining said nozzle in said aperture, said nozzle being provided with a longitudinal passage communicating with the interior of the container and providing means for restricting the quantity of fluent material dispensed from said container, said nozzle being further provided with a spraying head at its outer extremity, and means for dispersing fluent material within said spraying head prior to discharge therefrom.
